DESIGN FOR A COMBINED ERASER AND BRUSH WITH HOLDER THEREFOR

Earl C. Williams, Seattle, Wash., assignor to George H. Gill, Los Angeles, Calif.

Application January 29, 1945, Serial No. 117,653

Term of patent 7 years

(Cl. D74—7)

To all whom it may concern:

Be it known that I, Earl C. Williams, a citizen of the United States, residing at Seattle, in the county of King and State of Washington, have invented a new, original, and ornamental Design for Combined Eraser and Brush With Holder Therefor, of which the following is a specification, reference being had to the accompanying drawing, forming a part thereof.

bined eraser and brush with holder therefor showing my new design.

I claim:

The ornamental design for a combined eraser and brush with holder therefor, as shown.

EARL C. WILLIAMS.
